TRUSS

Harrison M. Turner, Kansas City, Mo.

Application May 21, 1934, Serial No. 726,694

7 Claims. (Cl. 128—108)

This invention relates to surgical appliances and particularly a device known as a truss, which is customarily worn about the torso so that one or more of the pads thereof might be disposed in supporting relation to a ruptured area, and the primary object of the invention is the provision of such a truss that is uniquely arranged with respect to the pads and has self-adjusting features which lend to the comfort of the wearer.

10 One of the important aims of the invention is to provide a truss having two pads thereon that are specially constructed to co-operate with the rupture-supporting pad in such fashion that the belt or supporting circumscribing member will not become bothersome to the patient, the said rupture-engaging pad being self-adjusting as natural movements of the patient take place.

Another object of this invention is to provide a specially formed truss pad that includes an air pocket which is formed to serve with the resilient material of the pad in presenting a cushion through which the pressure of the truss and its holding force is exerted to the body of the wearer.

25 A still further feature of this invention is to provide a strong, durable and simply constructed truss that will adjust itself to the wearer so that it will not restrict his movements or cause discomfort as a result of its presence.

30 Other objects of this invention will appear during the course of the following specification, referring to the accompanying drawing, which illustrates one example of an embodiment of the invention and wherein:

35 Figure 1 is a top plan view of a truss made to embody the invention.

Fig. 2 is an enlarged, detailed, sectional view through the main pad of the truss, taken on line II—II of Fig. 1.

40 Fig. 3 is a face view of said pad with the cushion entirely removed therefrom to reveal parts therebehind.

Fig. 4 is an enlarged, detailed, fragmentary, sectional view along line IV—IV of Fig. 3.

45 Fig. 5 is a fragmentary, face view of the ends of the interlocking links forming a part of the circumscribing member, and,

Fig. 6 is a vertical, central section through a truss pad embodying a modified form of this invention.

One of the contributing factors toward the rigidity of this truss is the manner of making the circumscribing member 10, which comprises a band 12 having a link 14 hingedly connected as at 16 to one end thereof and a link 18 hingedly connected as at 20 to the other end thereof. A headed pintle 22 is carried by link 18 and a series of inclined slots 24 are arranged to individually engage said pintle 22 when locking the circumscribing member 10 in operative position.

As such locking takes place, two novelly formed pads bear against the body of the wearer at the back. There is one of these pads supported by each link 14 and 18 respectively and the point of support is adjacent the respective hinge 16 and 20. To afford the maximum amount of resiliency and provide the greatest degree of comfort to the wearer, these pads 26 are mounted upon one end of a resilient arm 28 through the medium of a pin 30 which loosely engages the plate 32 of the pad 10 so that a wobbly fit is afforded. Thus not only can the pads 26 move toward and from links 14 and 18, but their faces may assume angles best suited for the surface being contacted. The other end of arm 28 is secured to its respective link 14 or 18 as the case may be by a securing clip 34. This clip circumscribes the link and end of arm 28 so that lateral displacement, other than that afforded by the resiliency of the arm 28, is precluded.

Plates 32, have an inturned, annular flange 36 at the edge thereof which is provided with a plurality of inwardly directed spurs. It is these spurs or flanges 36 that grip the annular edge of a sponge rubber pad or similar facing 38 and there is provided an air pocket between plate 32 and the back of facing 38 in a manner herein-after described with respect to the adjustable pad 40 that is carried by band 12 in the proximity of the actual rupture. This particular pad 40 is especially unique in that it extends at an angle downwardly and inwardly from a twisted length 42 formed on band 12. Thus an inward and upward pressure is afforded exactly where it is needed when the rupture is in the lower part of the abdomen.

A resilient, pad-supporting bar 44 has one end adjustably secured to band 12 at twisted length 42 through the medium of a securing screw 46 that is in screwthreaded engagement with a boss 48 formed on one side of twisted length 42. This screw 46 passes through the bifurcated end 50 of bar 44 and is maintained against accidental displacement by a lock washer 52 which is interposed between the head of screw 46 and the bifurcated end 50 of bar 44. Obviously, upon loosening screw 46 bar 44 may be completely withdrawn for replacement, or, bar 44 and all parts related thereto may be pivoted about the axis of screw 46.

The lower or opposite end of bar 44 carries a plate 54 having hole 56 formed therethrough to receive a pin 58 having head 60 formed thereon. This pin 58 is supported by bar 44 at a point spaced inwardly from the lower end thereof and when plate 54 is in the normal position, the upper edge of hole 56 bears against pin 58.

A struck-out portion 62 is integral with plate 54 and assists in creating a bearing which slidably engages bar 44. Since plate 54 and all parts

that can be possibly so constructed are made of aluminum, it is necessary to line the aforesaid bearing with a metal liner 64 which is turned in around bar 44 as shown in Fig. 4. Through 5 this construction plate 54 is free to move longitudinally along bar 44 within the limits defined by the distance between the ends of hole 56 which strike pin 58 to define its limit with respect to a path of travel.

10 Since it is desirable to yieldably maintain plate 54 in a given position, there is built into this unique pad a spring 66 made of a single piece of spring wire and having its ends crossed beneath pin 58. This spring 66 nests in plate 54 15 as shown in Figs. 2 and 3 and loops 68 are formed on each side so as to equalize the spring pressure that is exerted.

When the truss having a pad made as just set down is in place on the wearer, he may bend 20 or stoop with freedom because the distance between band 12 and plate 54 is decreased and increased as such bodily movement takes place. The resilient facing 70 is removably affixed to plate 54 in precisely the same manner as facings 38 are positioned on the aforesaid plates 32. In turned spurs 72 are formed at the annular periphery of plate 54 and grip the annular edge of resilient facing 70 as shown in Fig. 2. The diameter of the annular series of spurs 72 is 25 somewhat less than the normal diameter of facing 70 and when the latter is contracted to be gripped by spurs 72 it is arched outwardly as illustrated to present an air pocket 74, within which is housed the head of pin 58 and spring 66. Obviously, covering 70 is made of sponge rubber 30 or some analogous substance that will conform to the body contour at the zone of engagement and the inherent resiliency of this material is supplemented by the concave form of its inner side which acts with plate 54 to form the 40 pocket 74.

Pads 26 are made in the same manner and the advantage gained by such structural features will be found therein. It sometimes becomes necessary to cover the circumscribing member consisting of parts 12, 14 and 18, with leather or some suitable fabric and such may be done without altering the function of these parts.

A modified form of pad is illustrated in Fig. 6. 50 This pad comprises a plate 100 having the in-turned, spurred, annular peripheral flange 102 which engages the resilient member 104 which has a cavity 106 formed in the face thereof. Thus a ring-shaped engaging edge 108 is provided and to preclude any suction action, vent 55 holes 110 should be provided through the lower wall of resilient member 104.

The manner of using this truss, the advantages of the novel features built therein, and the unique 60 form of pads, have all been made clear throughout the foregoing specification, and while changes and modifications with respect to exact structural features might be made without departing from the spirit of the invention, it is understood 65 that the following claims define the limits with respect to the embodiment of the invention.

Having thus described the invention, what is claimed as new and desired to be secured by Letters Patent is:

70 1. A truss of the character described comprising a rigid circumscribing member; a plurality of opposed resilient arms mounted on said mem-

ber; and a pad on each arm respectively, said arms having attachment at one end, to the said circumscribing member, and extending inwardly from the latter with the respective pad mounted on the extended end whereby the circumscribing member is held in spaced relation to the body of the wearer, one of said pads being normally below the plane of the circumscribing member and slidably toward and from the same as the truss is on the body of the wearer. 10

2. A truss of the character described comprising a circumscribing member including a rigid, arched band and a rigid link hingedly connected to each end respectively of said band; a resilient arm having one end secured to each link respectively adjacent the hinge connection; a pad mounted on the free end of each arm respectively; and a pad supported by and in spaced relation to the said rigid arched band in substantially opposed relation to the aforesaid pads, said pad on the arch being yieldably supported for movement toward and from the plane of said band as the truss is worn. 15

3. In a truss of the kind set forth, a circumscribing member; a depending bar having one 25 end in engagement with said member; and a pad slidably mounted on said bar, said pad being yieldably held in a given position on the bar and adapted to move along the bar to and from said position as the truss is worn.

4. In a truss of the kind set forth, a circumscribing member; a resilient bar depending from said member; a plate slidably mounted on said bar; a spring to yieldably maintain the plate at the projected end of the bar; and a pad on one 35 side of the plate adapted to create pressure on the body of the wearer and to move with said plate to and from a position at the end of the bar as the truss is worn.

5. In a truss of the kind set forth, a circumscribing member; a resilient bar depending from said member; a plate slidably mounted on said bar; a spring to yieldably maintain the plate at the projected end of the bar and to allow movement of the plate along the bar as the truss is 40 worn; and a pad on one side of the plate, one end of said bar being pivotally, adjustably joined to the said member whereby to laterally secure the said pad in adjusted position. 50

6. A pad for trusses of the kind described comprising a supporting bar having a laterally projecting pin on one side thereof; a plate having an opening therethrough to receive the pin; a bearing formed on one side of the plate to slidably journal the bar; a spring on the other side of the plate to bear against the pin and yieldably maintain the plate at one end of a path of travel; and a resilient pad on the face of said plate. 55

7. A pad for trusses of the kind described comprising a supporting bar having a laterally projecting pin on one side thereof; a plate having an opening therethrough to receive the pin; a bearing formed on one side of the plate to slidably journal the bar; a spring on the other side of the plate to bear against the pin and yieldably maintain the plate at one end of a path of travel; and a resilient pad on the face of said plate, said pad being arched outwardly to form a pocket between the face of the plate and back of said pad 70 wherein is positioned the said pin and spring. 60
